UNITED STATES PATENT OFFICE

ERNST JULIUS SCHROEDER, OF AMERICUS, GEORGIA

HEATING SYSTEM

Application filed December 5, 1930. Serial No. 500,340.

This invention relates to fireplace construction, the primary object of the invention being to provide means whereby the heat from a fireplace which usually is spent on its passage through the chimney, may be utilized in heating water to supply a hot water heating system.

An important object of the invention is to provide a fire-back which may be readily and easily positioned in a fireplace to be subjected to the heat of the fire in the fireplace, for heating the water passing around the fire-back.

With the foregoing and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a front elevational view of a fireplace equipped with a fire-back constructed in accordance with the invention.

Figure 2 is a vertical sectional view through the device.

Figure 3 is a vertical sectional view through a modified form of the invention.

Referring to the drawings in detail, the fireplace with which the fire-back or water-back is used, is indicated by the reference character 5, the reference character 6 designating the grate of the fireplace.

The fire-back comprises a lower main section 6', a central section 7 and an upper section 8, the sections being secured together by means of the bolts 9 that extend through flanges formed integral with the sections.

Each section embodies an outer wall 10 and an inner wall 11, the walls being spaced apart to provide passageways, the inner walls of the sections being arranged so that when the ends thereof are brought together, a chimney is provided for the smoke and other products of combustion to pass from the fireplace.

As clearly shown by Figure 2 of the draw-

ings, the inner wall of the lower section 6', extends inwardly as at 12, from where it passes rearwardly at 13, connecting with the inner wall of the adjacent upper section.

Extending inwardly and downwardly from the inner wall of the section 6', are spaced flanges 13' that act as baffles to retard the upward movement of water or steam directed to the space between the outer and inner walls of the device.

The portion 12 of the inner wall is corrugated to increase the heating surface for heating the water contained in the pocket 14, adjacent to the section 7.

Arranged between the inner and outer walls of the lower section 6', is a baffle including an inclined wall 7' inclined towards the front of the fireplace, and a rearwardly inclined wall 8' connected with the rear wall of the section.

The reference character 15 designates the water inlet pipe which is connected with a suitable source of water supply not shown, for directing cold water to the space between the front and rear walls of the attachment. At the upper end of the device is the outlet pipe 16 through which the hot water passes to the radiators or spigots supplied with hot water from the device.

At the front of the fireplace is a sliding blower 17 which may be moved to regulate the passage of air into the fireplace. An air vent indicated at 18 is positioned at the top of the attachment to eliminate air pockets that would tend to retard circulation of the water in the system.

In the form of the invention as shown by Figure 3 of the drawings, the device comprises a lower section 20, central section 21 and an upper section 22, the sections being connected, as clearly shown, and positioned within the fireplace and the chimney to receive heat therefrom.

The inner wall of the lower section is formed with a plurality of offset portions 23 that increase the heating surface of the lower section, and provide wider contacting surfaces for the water that passes through the device.

A pipe 24 extends into the lower section 20 and supplies the attachment with water, while

at the upper end of the attachment, the pipe 25 provides the outlet pipe to supply hot water to the radiators or spigots connected therewith.

5 From the foregoing it will be obvious that due to the construction shown and described the heat which usually is wasted by its passage through the chimney, is utilized in heating water to furnish hot water to radiators which may be positioned in various rooms of a building to be heated by the heat from the fireplace.

I claim:

15 A fire place construction comprising a body portion fitted within a fire place opening, said body portion including a lower section, an up-

per section and an intermediate section, a grate in the lower section, said sections having spaced rear walls providing a water passageway, the passageway extending across the entire back of the body portion, the upper 70 portions of the rear walls of the lower section extending forwardly over the grate, the forwardly extended portion being corrugated increasing the heating surface thereof, spaced inwardly and downwardly extended flanges 75 extending into the passageway at a point below the corrugated portion, to control upward flow of water through the passageway, and inlet and outlet pipes communicating with the passageway.
